Des. 234,334
Patented Feb. 18, 1975

234,334

SUCTION CLEANER OR THE LIKE

Martin James Mims, London, England, assignor to The
Hoover Company, North Canton, Ohio

Filed Aug. 6, 1973, Ser. No. 386,011

Claims priority, application Great Britain Mar. 1, 1973

Term of patent 14 years

Int. Cl. D7—05

U.S. Cl. D7—165

FIG. 1

FIG. 2

FIG. 3

FIG. 4

FIG. 1 is a perspective view taken from the front of the suction cleaner embodying my design;

FIG. 2 is a perspective view taken from the rear thereof;

FIG. 3 is a front elevational view thereof; and

FIG. 4 is a left side elevational view of the side thereof.

I claim:

The ornamental design for a suction cleaner or the like, as shown and described.
